L. F. SCHILLING,
BED SPRING FABRIC.
APPLICATION FILED DEC. 24, 1915.

Patented June 11, 1918.

UNITED STATES PATENT OFFICE.

LOUIS F. SCHILLING, OF SALEM, OHIO.

BED-SPRING FABRIC.

1,269,316.

Specification of Letters Patent. Patented June 11, 1918.

Application filed December 24, 1915. Serial No. 68,533.

To all whom it may concern:

Be it known that I, LOUIS F. SCHILLING, a citizen of the United States, residing at Salem, in the State of Ohio, have invented 5 new and useful Improvements in Bed-Spring Fabrics, of which the following is a specification.

This invention relates to improvements in bed spring fabrics.

10 The invention proposes more particularly a bed spring fabric which is specially designed to be included in the equipment of a folding camp bed, such as is disclosed in my co-pending application Serial No. 76,409. 15 It is to be understood, however, that the utility of the invention is not confined to the instance just referred to but that bed spring fabrics, in accordance with the invention, may be used in connection with any 20 particular construction of bed.

The objects of the invention, briefly stated, are to provide a bed spring fabric which may be used without a mattress, and when so used, will afford a comfortable resting surface for 25 the occupant of the bed; which may be rolled into an exceedingly small compass; and which is inexpensive, strong, durable and sanitary.

30 A further object of the invention is to provide a bed spring fabric for use as stated which, while not in itself embodying any resilient elements, may be resiliently suspended from the end bars or rails of the bed similarly to any ordinary bed spring fabric 35 and, hence, will insure the comfort of the occupant of the bed.

Embodiments of the invention are illustrated in the accompanying drawings, wherein:—

40 Figure 1 is a plan view of a bed spring fabric in which the features of the invention are incorporated;

Fig. 2 is a detail cross-sectional view thereof on the line 2—2 of Fig. 1; and

45 Fig. 3 is a detail sectional view showing a slightly modified construction.

Similar characters of reference designate corresponding parts throughout the several views.

50 The fabric shown in Figs. 1 and 2 includes two sheets of stout canvas or equiva-

lent material 1 and 2 arranged face to face and secured to one another at suitable transverse intervals by longitudinal rows of stitching 3. The sheets 1 and 2, when 55 stitched together as stated, provide a support which may be of any desired longitudinal and transverse dimensions, preferably, the dimensions which are standard for ordinary bed spring fabrics. 60

The sheets 1 and 2 have under-turned longitudinal and transverse marginal portions 4 and 5, the longitudinal marginal portions 4 being secured by the rows of stitching 3 adjacent the sides of the fabric and the 65 transverse marginal portions 5 being secured by transverse rows of stitching 6 adjacent the ends of the fabric.

The longitudinal rows of stitching 3 are arranged in pairs, the rows of each pair being somewhat closely associated. The material between each two closely associated rows of stitching 3 provides a pocket 7 which extends longitudinally of the fabric from end to end thereof and incloses a longitudinal flexible reinforcing element 8. 70 The fabric is completed by the said reinforcing elements 8 which fit snugly in the pockets 7 and at their ends project slightly beyond said pockets and are provided with 75 eyes 9 through which the hook-like extremities of the spiral supporting springs (not shown) may be engaged, these springs being, as usual, secured to the end rails or bars of the bed frame. The reinforcing elements 8 80 are preferably in the form of flat link chains of the well known construction and the eyes 9 of said reinforcing elements are provided, in the embodiment disclosed, by the openings in the end links of the chains. 85 90

In Figs. 1 and 2 the mattress is unquilted and the portions of the canvas sheets between the reinforcing elements 8 lie against one another. With this construction, which is preferred, a blanket may be laid over the 95 fabric to provide a uniform supporting surface for the occupant of the bed.

However, if desired, the fabric may be quilted and an example of a quilted construction is shown in Fig. 3. In this case, 100 the upper sheet of canvas 1 is left measurably full or loose between the reinforcing

elements 8 to provide pockets 10 for the quilting material 11. In other respects, the construction shown in Fig. 3 is similar to that shown in Fig. 1.

- 5 The reinforcing elements 8 extend longitudinally of the bed spring fabric and bear the weight of the user of the couch and thus, as their designation implies, protect the canvas sheets 1 and 2. At the same time, they 10 insure the uniformity and efficiency of the support which the fabric, as a whole, including the canvas sheets, provides and thus prevent the fabric from sagging toward the center or throughout the area upon which 15 the greatest weight is imposed. The reinforcing elements 8 are preferably arranged at intervals of about two inches but their number for a bed spring fabric of given width is not absolute and may be varied 20 within certain limits. In any event, a sufficient number of these elements should be employed to provide the requisite strength for the bed spring fabric and to prevent sagging thereof. The reinforcing elements 25 8, when provided in number sufficient for the purposes just stated, will not, however, cause any discomfort to the occupant of the bed in case a blanket, quilt, or the like, is placed over the fabric. They will, moreover, while preventing sagging, permit of a measurable degree of flexibility and consequent yielding of the fabric, thus insuring the ease of the occupant of the bed.

The bed spring fabric described, while 30 having the advantages of strength and durability and of providing a uniform and comfortable support for the occupant of the bed, can be rolled into exceedingly small compass. Thus, where the fabric is included in 35 the equipment of a camp bed outfit, such as is disclosed in my co-pending application referred to, it may be rolled longitudinally into a compact cylinder, that is, a cylinder having its major axis transverse to the bed 40 spring fabric and having a sufficiently small diameter to enable its convenient storage on the running board of an automobile. For this reason, the fabric is highly advantageous in all cases where economy of space is 45 50 a vital consideration.

The form of fabric shown in Figs. 1 and 2 has the advantage that it can be readily washed or cleansed, should the need ever arise. The construction shown in Fig. 3 55 may also be washed or cleaned as need arises, although not so conveniently as the construction shown in Figs. 1 and 2.

The chains 8 may be readily renewed should it be found necessary or desirable. 60 These chains are preferably retained by friction in the pockets 7, having a snug fit in said pockets, as stated. It is to be noted, however, that the form of the chain links

and the relation of the chains to the canvas sheets will preclude the chains from substantially wearing the material of the pockets in which they are arranged.

Having fully described my invention, I claim—

1. A bed spring fabric of canvas sheeting 70 adapted to afford a resting surface for the occupant of the bed and having longitudinal parallel pockets extending from end to end thereof and arranged at regular transverse intervals, and flexible reinforcing and 75 supporting elements extending through said pockets and having projecting attachment terminals, said elements being in somewhat close association with one another and of such construction that the fabric may be 80 rolled longitudinally into a compact cylinder.

2. A laminated canvas bed spring fabric adapted to afford a resting surface for the occupant of the bed and having its sheets 85 connected by parallel longitudinal rows of stitching arranged in pairs at regular transverse intervals and provided with a longitudinal pocket between the rows of each pair extending from end to end thereof and flexible reinforcing and supporting elements 90 extending through said pockets and having projecting attachment terminals, said elements being in somewhat close association with one another and of such construction 95 that the fabric may be rolled longitudinally into a compact cylinder.

3. A bed spring fabric of canvas sheeting, adapted to afford a resting surface for the occupant of the bed and having longitudinal parallel pockets extending from end to end thereof and arranged at regular transverse intervals and reinforcing and supporting flat link chains extending through and 100 projecting beyond said pockets, said chains 105 being in somewhat close association with one another and of such construction that the fabric may be rolled longitudinally into a compact cylinder.

4. A laminated canvas bed spring fabric 110 adapted to afford a resting surface for the occupant of the bed and having its sheets connected to parallel longitudinal rows of stitching arranged in pairs at regular transverse intervals and provided with a longitudinal pocket between the rows of each pair 115 extending from end to end thereof and reinforcing and supporting flat link chains extending through and projecting beyond said 120 pockets, said chains being in somewhat close association with one another and of such construction that the fabric may be rolled longitudinally into a compact cylinder.

5. A bed spring fabric of canvas sheeting 125 adapted to afford a resting surface for the occupant of the bed, and flexible reinforcing

and supporting elements over which said resting surface extends, said elements being disposed longitudinally of said sheeting in somewhat close association with one another
5 and being of such construction that the fabric may be rolled longitudinally into a compact cylinder, said elements having projecting attachment terminals, the sheeting having means for holding said elements

thereto and definitely determining the extent of their spacing from one another.

In testimony whereof I have hereunto set my hand in presence of two subscribing witnesses.
